By Charles P. Hannigan,
Attorney.

UNITED STATES PATENT OFFICE.

EMMA L. DUNNING, OF PROVIDENCE, RHODE ISLAND.

VAPORIZER.

No. 888,393.

Specification of Letters Patent.

Patented May 19, 1908.

Application filed August 3, 1907. Serial No. 386,996.

To all whom it may concern:

Be it known that I, EMMA L. DUNNING, a citizen of the United States, residing at the city of Providence, in the county of Providence, State of Rhode Island, have invented 5 certain new and useful Improvements in Vaporizers, of which the following is a specification.

My invention relates to a device adapted 10 to contain a chemical liquid for purifying the air in sick-rooms, work-shops, and other places where pure fresh air is required. The object in view being to provide a liquid receptacle with means for throwing off the 15 vapor of said liquid in order to destroy the foul odor in the atmosphere of sick-rooms, work-shops, or other places where air may become impure.

A further object of my invention is to provide 20 a device of this character with a locking means to insure a proper working of the interior parts from being tampered with by a miscreant, while the device is in use.

To the above ends essentially my invention 25 consists in the novel construction and combination of parts, as hereinafter described and claimed.

In the accompanying sheet of drawings, Figure 1 represents a perspective view of my 30 improved vaporizer. Fig. 2 is a transverse sectional view of the device, taken in line $x-x$ of Fig. 1, showing the device in operative position upon the wall of a room, and, Fig. 3 is a modification of the cover-closing 35 means for the receptacle.

Like reference characters indicate like parts.

a designates a rectangular-shaped receptacle having a hinged cover b and integral brackets c, c , which are provided with holes 40 d, d to receive screws e, e therethrough for securing the device to the wall f of a room.

A layer of absorbent material g is folded upon a rod-extension h whose ends are secured centrally on the end walls a', a' of the 45 receptacle, and this layer of absorbent material is partially submerged in my specially prepared chemical liquid, designated by reference letter i . The capillary action of the absorbent material g draws up the liquid 50 from its volume i , so that the portion of the absorbent material above the level of the liquid is kept continually saturated and the vapor caused by the constant evaporation of the liquid, from this distended portion of the 55 absorbent material, passes out through perforations j, j , formed in the walls of the de-

vice, and co-mingles with and destroys the foul odor in the atmosphere of a room.

The cover b , which is hinged to the rear longitudinal wall of the receptacle, as at a point b' in Fig. 2, has a centrally depending tongue b^2 secured by solder upon said cover, and said tongue is provided with an opening b^3 to receive therethrough a pin k , which is secured to the front wall of the receptacle and 60 projecting within the same. The tongue b^2 is of spring-metal and has its lower portion curved, in order to pass over in contact upon the point of the pin k , which, when the cover is closed, enters the opening b^3 of the spring- 65 tongue b^2 and holds the device in a locked 70 condition, in the manner shown in Fig. 2.

To unlock the device, a common pin l is used for entering through a fine perforation m formed in the front wall of the receptacle 75 and forcing the spring-tongue b^2 from its connection with the pin k to the dotted position indicated in Fig. 2, when the cover will then be free to swing open.

The manner of unlocking the device acts 80 as a puzzle to any other than the owner or person having charge of the device, thus the interior parts are protected and a proper working of the device is assured.

As a modification to the concealed means 85 of locking the device, as described, the cover b may be independent of the receptacle and have its longitudinal edges curled, as at n, n in Fig. 3, in order to slide and hold by frictional contact upon the beaded edges n', n' , 90 formed on the front and rear walls of the receptacle.

By my construction and arrangement of parts, I provide a neat and useful device for the purpose intended, and having means to 95 insure an effective working while the device is in use.

What I claim and desire to secure by Letters-Patent, is—

The combination of the receptacle a provided with vent openings j, j ; the rod-extension h ; the layer of absorbent material g ; the pin k ; and the cover b hinged to said receptacle and having the tongue b^2 provided with an opening to receive said pin therethrough, 100 substantially as set forth.

In testimony whereof I affix my signature in presence of two witnesses.

EMMA L. DUNNING.
